HAIR TRIMMER

Norbert Shaeffer, Los Angeles, Calif., assignor, by
mesne assignments, to Cutter Corporation, a
corporation of Delaware

Application January 8, 1949, Serial No. 69,885

6 Claims. (Cl. 30—30)

1

This invention relates to a hair cutting comb of the general type disclosed in the copending application of Roy P. M. Davis entitled "Hair Cutting Comb," filed August 19, 1946, Serial No. 691,448, now Patent No. 2,519,954, issued August 22, 1950. Combs of this type employ a movable sharpened blade in connection with the teeth on the comb so that hair may be cut or trimmed or shaved as desired.

The principal object of this invention is to provide a novel form of drive means for moving the sharpened blade relative to the teeth of the comb. The drive means employed in commercially available hair trimming combs is similar in many respects to the drive means shown in the Davis application referred to. Such drive means employs a rack formed on the blade carrier which merges with a pinion gear carried on the stationary portion of the comb structure. The pinion gear is turned by means of an adjusting knob to change the position of the sharpened blade with respect to the teeth of the comb. A disadvantage of drive means of this type is that the drive is reversible, that is, not only can the gear drive the rack but the rack can turn the gear. The blade carrier is therefore not locked in place by the drive means but may shift slightly while in use to vary the adjusted position of the sharpened blade.

In accordance with the present invention I provide a nonreversible drive for moving the blade carrier relative to the comb teeth so that the carrier and blade are automatically locked in adjusted position. Stresses imposed on the blade or carrier during use do not change the position of the blade with respect to the comb teeth because the drive for moving the carrier is of nonreversing character. I prefer to employ a worm gear, screw and nut, cam and follower or other form of nonreversible drive.

It is a further object of my invention to provide a novel form of blade carrier guided for movement on the body of a toothed comb.

Another object is to provide a novel form of rotary member for varying the position of the blade carrier with respect to the comb body.

Other and more detailed objects and advantages will appear hereinafter.

In the drawings:

Figure 1 is a plan view showing a preferred embodiment of my invention.

Figure 2 is a similar view partly broken away to show details of construction.

Figure 3 illustrates the manner in which a conventional "safety razor" blade is attached to the carrier.

Figure 4 is a longitudinal sectional view taken substantially on the lines 4—4 as shown in Figure 1.

Figure 5 is a transverse sectional view taken substantially on the lines 5—5 as shown in Figure 1.

Figure 6 is a transverse sectional view taken

2

substantially on the lines 6—6 as shown in Figure 1.

Figure 7 is a transverse sectional elevation taken substantially on the lines 7—7 as shown in Figure 2.

Referring to the drawings, the comb body generally designated 10 is provided with a first series of relatively long teeth 11 and a second series of double teeth 12. The teeth in the second series 12 are separated by relatively long slots 13. The back 14 of the comb lies adjacent the double teeth 12 while a third series of trimmer teeth 15 is provided on the comb body opposite the series 12. The comb body 10 is provided with a platform or sliding surface 16 intermediate the end 17 and the transverse groove 18. A sharpened blade 19 is adapted to rest on this sliding surface 16. This blade 19 may be of the conventional "safety razor" type if desired. The blade 19 is attached to a carrier 20 having a lower flat surface 21 adapted to contact the upper surface of the blade 19. A pair of protuberances 22 extend downwardly from the flat surface 21 to engage within the noncircular openings 23 provided in the blade 19. The protuberances 22 are proportioned so that they extend through the blade 19 and are resiliently held by the portions of the blade adjacent the recesses 23 so that the blade 19 is attached to and moves with the carrier 20. A pair of shallow troughs 24 is provided in the sliding surface 16 on the comb body to provide clearance for the protuberances 22.

A transverse rib 25 extends along one side of the carrier and is adapted to travel in the transverse slot 18 formed in the comb body. On the same end of the carrier and adjacent the rib 25 is an outwardly projecting follower lug or tooth 26. A worm gear or rotary cam element 27 is provided with a helical groove 28 which receives the follower 26 in cooperative relationship. The rotary element 27 may be provided with trunnions 27a at its opposite ends which are received within bearing recesses provided in the comb body 10 and in the cap member 29. This cap member 29 is provided with a lip 30 which overlies a portion of the carrier 20 at one end to prevent disassembly from the comb body 10. A lip 31 adjacent the end 17 of the comb body also overlies a portion of the carrier 20. The cap 29 is secured to the body 10 by any convenient means, and as shown in the drawings this may include a plurality of dowel pins 32 formed on the member 10 and extending into cooperating recesses 33 provided in the cap 29. The dowels 32 fit tightly within the recesses 33 to prevent accidental disassembly of the parts. An opening 34 is formed through the comb body 10 and through the cap 29 and the rotary element 27 is free to turn within this opening. When the rotary element is turned about the axis of its trunnions 27a the follower or tooth 26 is caused to travel in the helical groove 28, thereby moving the carrier 20 relative to the comb

body 10. The carrier is guided for movement by means of the inter-engaging rib 25 and slot 18 and therefore moves in a direction parallel to the axis of the trunnions. The sharpened blade 19 is fixed relative to the carrier 20 so that its position may readily be adjusted by turning the rotary element 27. An indicator 35 may be provided on the carrier 20 which cooperates with a reference mark 36 on the cap 29 to provide a visual indication of the adjusted position of the sharpened blade 19. The position of the blade may also be visually determined by noting the position of the sharpened edge of the blade with reference to the trimmer teeth 15. When it is desired to change blades or to reverse the blade to use the other edge, the rotary element 27 is turned to the position shown in Figure 2. This action disengages the follower or tooth from the helical groove so that the carrier may be withdrawn laterally. The position of the sharpened blade may then be reversed to present a new cutting edge or a new blade may be installed on the carrier. The carrier is repositioned on the comb body with the tooth or follower 26 received within the helical groove 28.

It will be noted by reference to Figures 1 and 2 that the sharpened blade 19 is adapted for cutting action adjacent the trimmer teeth 15 and also projects downwardly for cooperative cutting action with the teeth 12. In the position shown in Figure 6 the sharpened blade 19 overlies a portion of the circular recesses 37 at the inner end of each of the long slots 13. Both sharpened edges of the blade are therefore available for use.

The term "nonreversing" as used in this specification and in the claims is intended to mean a drive in which the driven member is incapable of becoming a driving member, and vice-versa. More specifically, the term is intended to mean that the rotary element 27 cannot be driven by the follower lug or tooth 26, but it is not intended to infer by the use of the term "nonreversing" that the rotary element can be rotated in one direction only.

Having fully described my invention, it is to be understood that I do not wish to be limited to the details herein set forth, but my invention is of the full scope of the appended claims.

I claim:

1. In a hair trimming device, the combination of a comb body; a carrier for a sharpened blade; means for mounting the carrier for sliding movement relative to the comb body, said means including an apertured cap secured to the comb body and having a lip overlying a portion of the carrier; and nonreversible drive means for moving the carrier on the comb body, said drive means including a worm gear mounted for rotary movement on the comb body and extending through the apertured cap, and an element fixed to the carrier meshing with the worm gear.

2. In a hair trimming device, the combination of a comb member; a carrier member adapted to carry a sharpened blade; means for mounting the carrier member for sliding movement relative to the comb member, said means including axially spaced parallel lips on the comb member defining parallel transverse channels, the extreme ends of the carrier member being guided in said channels; and nonreversible drive means for moving the carrier member on the comb member, said drive means including a worm gear mounted for rotary movement on one member and meshing with a lug element fixed to the other member.

3. In a hair trimming device, the combination

of a comb member having axially spaced parallel lips defining parallel transverse channels; a carrier for a sharpened blade, the carrier being mounted for sliding movement relative to the 5 comb member and having its extreme ends guided in said channels, the carrier being provided with a follower; a rotary element having a helical groove to receive the follower in said helical groove; and means supporting the rotary element 10 on the comb member for turning movement about an axis parallel to the direction of movement of the carrier.

4. In a hair trimming device, the combination of a comb member; a carrier for a sharpened 15 blade; means for mounting the carrier for movement relative to the comb member; nonreversible drive means for moving the carrier on the comb member, said drive means including a rotary element provided with axial trunnions; a cap fixed 20 on the comb member and cooperating therewith to provide bearings for said trunnions, the cap and comb member having aligned openings to receive the rotary element; and a follower element fixed to the carrier and cooperating with 25 the rotary element to move the carrier when the rotary element is turned.

5. In a hair trimming device, the combination of: a comb body having a transversely extending lip adjacent one end defining a transverse channel, the body having a transverse groove axially spaced from said channel, a carrier for a sharpened blade mounted for sliding movement relative to the comb body, the carrier having a rib slidably received within said groove and having an extreme end remote from said rib guided for sliding movement within said channel, an axially projecting follower on the carrier adjacent said rib, a rotary element having a groove extending axially and circumferentially to receive said follower, the rotary element being provided with axial trunnions, a cap fixed on the comb body and cooperating therewith to provide bearings for said trunnions, the cap and comb body having aligned openings to receive the rotary element, and the cap having a lip overlying a portion of the carrier adjacent said rib.

6. A hair cutting device for use with a blade comprising in combination: a comb member, a blade positioning member for holding a cutting edge of the blade in operating position with respect to the comb member, one of said members having a transversely extending channel positioned adjacent one end of the positioned blade, a driving mechanism mounted on said channelled member, and a following means positioned on the other member and extending into said channel adjacent said one end of the positioned blade, whereby the driving mechanism may move the following means in the channel causing a transverse movement between the members.

NORBERT SHAEFFER.
